UNITED STATES PATENT OFFICE.

SAMUEL HALTOM, OF MOUNT ENTERPRISE, ASSIGNOR OF ONE-FIFTH TO
CHAS. A. OLIVER, CALVIN J. BELL, AND JOHN BELL, OF LAWSONVILLE,
TEXAS.

CAR-COUPING.

SPECIFICATION forming part of Letters Patent No. 309,944, dated December 30, 1884.

Application filed August 18, 1884. (No model.)

To all whom it may concern:

Be it known that I, SAMUEL HALTOM, of Mount Enterprise, in the county of Rusk and State of Texas, have invented certain new and 5 useful Improvements in Car-Couplings; and I do hereby declare the following to be a full, clear, and exact description of the invention, such as will enable others skilled in the art to which it pertains to make and use it, reference 10 being had to the accompanying drawings, which form part of this specification.

My invention relates to an improvement in car-couplings; and it consists, first, in the combination, with the draw-head having a flange 15 extending vertically upon one of its sides, of a hook, which is pivoted in the opposite side of the draw-head, and which is adapted to catch in the flange that is formed upon the adjacent draw-head when the cars are run together, a weight which is attached to the hook 20 for the purpose of keeping it normally engaged with the adjacent draw-head, and a gravity-latch which is adapted to engage with the catch that is formed upon the inner end of 25 the hook for the purpose of securing said hook in position when the cars are uncoupled; second, in the combination of a frame which is pivoted on the under side of the cars, a shaft 30 which is journaled therein, and which is provided with a drum at its upper end and a seg- 35 mental worm-pinion at its lower end, with a worm which is formed upon one of the axles for engaging with the worm-pinion, and a bent lever which is pivoted at the front end of the 40 car, and which projects a suitable distance in front of the draw-head, and which is connected at its lower end to the swinging frame, and a bent lever which is provided with a drum, and which is pivoted in the rear end of 45 the car, and which is connected to the drum that is secured to the upper end of the shaft in the swinging frame by a chain, for the purpose of preventing the train from becoming coupled to a car which is standing upon the track when the train is backed down to said car, as will be more fully described herein-after.

The object of my invention is, first, to pro-

vide a coupling which is automatic in its operation when cars are brought in contact; and, 50 secondly, to provide means for preventing a train which is coupled by means of my couplers from becoming attached to a car which may be standing on the track when the train is backed down to said car.

In the accompanying drawings, Figure 1 is 55 a side elevation, partly in section, of my invention complete. Fig. 2 is a bottom plan view of the same.

A represents a car, and B the tender of the 60 locomotive. This tender has pivoted to its under side a bent foot-lever, C, the upper end of which projects slightly above the floor of the tender, while its lower rear end extends back and comes in contact with the bent lever 65 D, which is pivoted in the front end of the adjacent car. This lever D is connected at its lower end by means of a chain or bail, E, with a swinging frame, F, which is pivoted to the under side of the car, as at G, and in 70 which frame is journaled the shaft H, which has a drum, I, secured to its upper end, and a segmental worm-pinion, K, secured to its lower end, which pinion, when the upper end of the lever D is raised by means of the foot-lever C, meshes with a worm, L, which is 75 formed upon the axle M.

N represents a fender-lever, which is bent into the shape here shown, and which is pivoted to the under side of the rear end of the 80 car A, and has a drum, O, rigidly secured to its pivotal portion. To this drum is secured a chain, P, which connects it with the drum I. The operation of this part of my invention will be set forth hereinafter.

My coupling consists of draw-heads Q, which are each provided with a flange, R, upon one side, and which have hooks T, pivoted between ears S, that are formed upon the opposite side. These hooks are provided at 90 their inner pivotal ends with the extensions V, to which are secured the chains W, which pass over sheaves X, which are journaled in openings Y that are formed in the under sides of the draw-heads. The lower ends of these 95 chains are secured to the bent weighted le-

vers Z, which are pivoted in the draw-heads, as at A'.

B' represents a notch, which is formed in the rear end of each of the hooks, and C' represents a gravity-latch, which, when the hook is opened into the position shown in dotted lines in Fig. 2 when the cars are uncoupled, catches in behind the shoulder of the notch, and this locks the hook in its open position. The function of the weighted lever is to keep the hook normally closed in contact with the adjacent draw-head when the cars are coupled. The draw-heads Q are secured in ways D' on the under sides of the cars, and are given a longitudinal play in said ways by means of the rearwardly-projecting headed bolts E' and the buffer-springs F', which are of the ordinary construction.

G' represents an abutment, which is secured to the ways next adjacent to and in rear of the levers C'. When the cars come in contact, the draw-heads move backward in their ways against the tension of the buffer-springs, and the gravity-latches C' strike against the abutments G' and become disengaged from the notches of the hooks, and the weighted-levers, which are attached to said hooks, cause them to spring in and come in contact with the flanges of the opposite draw-heads, and thus couple the cars together. Should the train be backed against a car which may be standing on the track, and to which it is not desired that the train shall be coupled, as is frequently the case in switching, the engineer places his foot upon the lever C, which raises the lever D of the forward car, which motion places the segmental pinion K in gear with the worm upon the shaft, and by means of the drums I and O and the chain P raises the fender-lever N, which raises the lever D of the next adjacent car, and so on through the entire train until the rear car is reached. When this rear car comes in contact with the car standing on the track, the fender-lever strikes against said car, and thus prevents said car from becoming coupled to the train.

Secured to each of the hooks T is a rope, H', which passes over a sheave that is secured to the end of the car, and from thence up and over sheaves which are placed at the upper sides of the car, and from thence down and around a sheave which is placed upon the opposite side of the car at its lower side. By means of this rope the hooks can be detached from the adjacent draw-head by a person standing upon the top of the car, or upon the ground at either side thereof.

A coupling thus constructed is exceedingly simple, cheap, and efficient, and its adoption

would insure a great saving of time, labor, and loss of life.

Having thus described my invention, I claim—

1. The combination of the draw-head provided with a flange upon one of its sides, ways for securing said draw-head in place and allowing it a longitudinal movement, an abutment which is secured to said ways upon one side, a hook which is pivoted in the draw-head on the side opposite to the flange, which hook is provided with a weight for keeping it normally closed, and which has a notch formed upon its pivotal end, and a latch which is pivoted to one side of the draw-head, and which is adapted to catch in the notch in the hook for the purpose of keeping the hook open, whereby when the cars are coupled the latch, as the draw-head is driven in, will strike against the abutment and release its hold upon the hook, substantially as described. 80

2. The combination, with a car provided with an automatic coupling, of the lever D, pivoted to said car, a worm formed upon one of the axles, a swinging frame pivoted beneath the car and having a shaft journaled therein, to which shaft is secured a segmental gear at its lower end and a drum at its upper end, a fender-lever which is pivoted in the rear end of the car and which has a drum secured to its pivotal end, a chain for connecting said drum with the drum upon the upper end of the shaft in the swinging frame, and a means for connecting the lower end of the swinging frame with the lower end of the bent lever D, all combined and arranged to operate substantially in the manner and for the purpose described. 90

3. The combination of a car provided with an automatic coupling with a fender-lever which is pivoted to the rear end of the car, and means for causing said fender-lever to be raised when backing the car, for the purpose set forth, substantially as described. 100

4. The combination of a car provided with an automatic coupling with a fender-lever which is pivoted to the rear end of the car, the swinging frame F, having shaft H and drum I, chain P, and means for causing the drum I to rotate when backing the car for the purpose of winding the chain and raising the fender-lever, substantially as described. 110

In testimony whereof I affix my signature in presence of two witnesses.

SAMUEL HALTOM.
